DUST EXHAUSTING DEVICE FOR
SURFACING WHEELSHenry G. Eisler, Wilmette, Ill., assignor to The
Bell & Howell Company, Chicago, Ill., a corpora-
tion of Illinois

Application August 13, 1943, Serial No. 498,597

4 Claims. (Cl. 51—273)

My invention relates to a dust exhausting device for surfacing wheels, such as grinding and polishing wheels, and involves a usual dust exhausting hood spacedly shrouding a rotatory surfacing wheel and provided with a work opening at which work is presented to the wheel and with an exhaust outlet spaced from the work opening and connected with an exhausting fan for drawing air and with it dust resulting from surfacing operations from the work opening into the hood and out of the hood through the outlet for suitable disposal, so that the dust is not dispersed into the surrounding atmosphere.

The general object of the invention resides in the provision in a dust exhausting device of the above character, of a novel and effective means whereby the passage of air through the exhausting hood from the work opening to the outlet thereof is adjustably controlled so that, while adequate and efficient dust removal is assured for all conditions, the amount of air drawn through the work opening of the hood from the surrounding atmosphere may be maintained at a minimum consistent with the instant working conditions and so that the passage of air through the hood may be stopped when the surfacing wheel is not being used.

Accordingly, the amount of air which is withdrawn from a room in which one or more surfacing wheels equipped with my invention is or are installed may be minimized, with the result that such withdrawal of air may have a minimum undesirable effect upon the control of the atmosphere of the room, which is of considerable importance where a considerable number of grinding wheels are installed in a room in which the atmosphere is air conditioned.

The invention will be better understood by reference to the accompanying drawing in which—

Figure 1 is a partial front elevation of a surfacing wheel equipped with my invention;

Figure 2 is a side elevation of the same; and

Figure 3 is a sectional view in elevation similar to that of Figure 2.

Referring to the drawing, 1 designates a driving motor, upon the rotating shaft 2 of which is secured, as designated at 3, a surfacing wheel 4 for rotation therewith, the wheel shown being a polishing wheel.

A dust exhausting hood 5 of generally conventional characteristics is secured in position spacedly shrouding the polishing wheel 4, and is provided with a front work opening 6 at which work may be presented to the wheel for surfacing and with an exhausting outlet 7 in the form of

5 a conduit communicating with the interior of the hood and spaced from the work opening peripherally of the wheel and extending tangentially of the wheel in the direction of rotation thereof, which direction is indicated by the arrow 8 in Figure 3. The hood 5 is also provided with an air inlet 9 in the form of a conduit communicating with the interior of the hood and spaced from the work opening peripherally of the wheel and extending tangentially of the wheel in the direction opposite to the direction of rotation thereof and substantially aligned with the outlet 7.

10 A damper plate 11 is disposed within the hood 5 and extends across between the side walls 12 thereof and extends peripherally of the wheel 4 between the work opening 6 and the outlet 7, and is disposed in continuing relation with the outlet, and is curved correspondingly with the periphery of the wheel so that the concave surface thereof faces the periphery of the wheel.

15 The damper plate 11 is pivotally mounted on the side walls 12 of the hood 5, as designated at 13, with its work opening corresponding end 14 spaced outwardly from the periphery of the wheel 4 and disposed substantially at the peripheral wall 15 of the hood and on an axis parallel to the axis of the wheel and spaced outwardly from the periphery thereof and disposed substantially at said work opening corresponding end. As so pivotally mounted, the outlet corresponding end 16 of the damper plate 11 is adjustable toward and away from the periphery of the wheel 4 to adjustably control the passage of air through the hood from the work opening 6 to the outlet 7 between the damper plate and the periphery of the wheel, as best shown in Figure 3, and may be adjusted into close proximity to the wheel, as shown by dot and dash lines in this figure, to substantially stop the passage of air between the damper plate and the periphery of the wheel when the wheel is not being used.

20 The damper plate 11 extends beyond the inlet 9 in the direction toward the outlet 7, so that, as it is adjusted toward and away from the periphery of the wheel, it is also adjusted out of and into obstructing relation with the inlet 9. As a result, adjustment of the damper plate 11 does not have any tendency to vary the partial vacuum at the outlet 7 for the reason that as the opening between the damper plate and the wheel is decreased, the opening of the air inlet 9 is increased and vice versa.

25 The damper plate 11 is positioned in the various adjustments thereof by means of a suitable releasable clamping device, generally designated

at 17, operable through a segmental slot 18 through one side wall of the hood 5 and connected with a lug 19 on the damper plate at the intermediate portion thereof.

A second damper plate 21 is disposed within the hood 5 and extends across between the side walls 12 thereof and extends peripherally of the wheel 4 between the work opening 6 and the outlet 7 in the direction with respect to the outlet 7 opposite that in which the damper plate 11 extends. The damper plate 21 is curved correspondingly with the periphery of the wheel 4 so that the concave surface thereof faces the periphery of the wheel.

The damper plate 21 is pivotally mounted on the side walls 12 of the hood 5 by means of a pivot shaft 22 journaled on the side walls of the hood and on which the damper plate 21 is secured at its work opening corresponding end 23. By means of the pivot shaft 22, the damper plate 21 is pivotally mounted with its work opening corresponding end 23 spaced outwardly from the periphery of the wheel 4 and disposed substantially at the peripheral wall 15 of the hood and on an axis parallel to the axis of the wheel and spaced outwardly from the periphery thereof and disposed substantially at the work opening corresponding end 23. As so pivotally mounted, the outlet corresponding end 24 of the damper plate 21 is adjustable toward and away from the periphery of the wheel 4 to adjustably control the passage of air through the hood from the work opening 6 to the outlet 7 between this damper plate and the periphery of the wheel, as best shown in Figure 3.

The damper plate 21 is positioned in the various adjustments thereof by means of a suitable clamping device, generally designated at 25, carried on an arm 26 secured on the pivot shaft 22 and operable through a segmental slot 27 through one side wall of the hood 5.

The damper plate 11 controls the passage of air through the hood from the work opening 6 to the outlet 7 in the direction of rotation of the wheel 4, which is the direction in which dust, resulting from work presented to the wheel, is thrown, and air carrying the dust is drawn into the hood between this damper plate and the wheel and exhausted through the outlet 7, air also passing from the inlet 9 into the outlet opening 7 for the purpose above described, as indicated by the arrows 28 in Figure 3.

The damper plate 21 is preferably adjusted closely adjacent the wheel 4 to substantially prevent air passing through the hood to the outlet 7 in the direction opposite the direction of rotation of the wheel, adjustment of this damper plate accommodating for surfacing wheels of different sizes and for the wearing down thereof.

The curvature of the damper plates, providing concave surfaces facing and extending correspondingly with the periphery of the wheel together with the location of their pivotal axes and work opening corresponding ends, is desirable in that air passages gradually decreasing in the direction of movement of the air are provided. This is particularly true of the damper plate 11, a relatively large air opening being provided by this damper plate at the work opening 6.

While I have thus described my invention, I do not wish to be limited to the precise details described, as changes may be readily made without departing from the spirit of my invention,

but having thus described my invention, I claim as new and desire to secure by Letters Patent the following:

1. In a device of the character described, the combination with a rotatory surfacing wheel and a dust exhausting hood spacedly shrouding the same and provided with a work opening and an exhausting outlet spaced from said work opening peripherally of said wheel and extending tangentially of said wheel in the direction of rotation thereof and provided with an air inlet spaced from said work opening peripherally of said wheel and extending tangentially of said wheel in the direction opposite the direction of rotation thereof and substantially aligned with said outlet, of a damper plate within said hood and extending peripherally of said wheel between said work opening and said outlet and disposed in continuing relation with said outlet and extending beyond said inlet in the direction toward said outlet and said damper plate being curved correspondingly with the periphery of said wheel and pivotally mounted with its work opening corresponding end spaced outwardly from the periphery of said wheel and on an axis generally parallel to the axis of said wheel and spaced outwardly from the periphery thereof and disposed in the region of said work opening corresponding end for adjustment of the outlet corresponding end of said damper plate toward and away from the periphery of said wheel and out of and into obstructing relation with said inlet.

2. In a device of the character described, the combination with a surfacing wheel and a dust exhausting hood spacedly shrouding the same and provided with a work opening and an exhausting outlet spaced from said work opening peripherally of said wheel, of two damper members within said hood and extending peripherally of said wheel between said work opening and said outlet respectively in opposite directions with respect to said outlet and independently pivotally mounted with their work opening corresponding ends spaced outwardly from the periphery of said wheel on axes generally parallel to the axis of said wheel and spaced outwardly from the periphery thereof and disposed in the regions of said work opening corresponding ends for adjustment of the outlet corresponding ends of said damper members toward and away from the periphery of said wheel.

3. In a device of the character described, the combination with a rotatory surfacing wheel and a dust exhausting hood spacedly shrouding the same and provided with a work opening and an exhausting outlet spaced from said work opening peripherally of said wheel and extending tangentially of said wheel in the direction of rotation thereof, of two damper members within said hood and extending peripherally of said wheel between said work opening and said outlet respectively in opposite directions with respect to said outlet and one of which is disposed in continuing relation with said outlet and said damper members having the surfaces thereof facing the periphery of said wheel of concave curvature angularly of said wheel and being independently pivotally mounted with their work opening corresponding ends spaced outwardly from the periphery of said wheel and substantially at the peripheral wall of said hood and on axes generally parallel to the axis of said wheel and spaced outwardly from the periphery thereof and disposed in the regions of said work opening corresponding ends for adjustment of the outlet corresponding ends of said

damper members toward and away from the periphery of said wheel.

4. In a device of the character described, the combination with a rotatory surfacing wheel and a dust exhausting hood spacedly shrouding the same and provided with a work opening and an exhausting outlet spaced from said work opening peripherally of said wheel and extending tangentially of said wheel in the direction of rotation thereof and provided with an air inlet spaced from said work opening peripherally of said wheel and extending tangentially of said wheel in the direction opposite the direction of rotation thereof and substantially aligned with said outlet, of two damper plates within said hood and extending peripherally of said wheel between said work opening and said outlet respectively in opposite directions with respect to said outlet and one of

5 which is disposed in continuing relation with said outlet and extends beyond said inlet in the direction toward said outlet and said damper plates being curved correspondingly with the periphery of said wheel and independently pivotally mounted with their work opening corresponding ends spaced outwardly from the periphery of said wheel and substantially at the peripheral wall of said hood and on axes generally parallel to the axis of said wheel and spaced outwardly from the periphery thereof and disposed in the regions of said work opening corresponding ends for adjustment of the outlet corresponding ends of said damper plates toward and away from the periphery of said wheel and the outlet corresponding end of said one damper plate out of and into obstructing relation with said inlet.

HENRY G. EISLER.
